X-RAY TUBE

Maurice Poitevin, Meudon, France

Application November 30, 1946, Serial No. 713,354
In France December 14, 1945

8 Claims. (Cl. 313—57)

1

The present invention has for its object an improvement in electronic X-ray tubes and permits of obtaining focus of extreme sharpness.

It consists in giving to the axis of the filament which emits the electrons a radius of curvature of which the centre is located on or near the front surface of the anticathode, this filament being situated in a focussing member which may also be of curved form.

Under these conditions, in the plane containing the curved axis of the filament, the lines of electric force emitted by this filament converge first towards the centre of curvature of the latter, then, become perpendicular to the surface of the anticathode. The electrons emitted by the filament, the paths of which are approximately the straight prolongations of the initial part of the lines of force, then converge towards the centre of curvature of the filament, so that, if the centre is disposed on the face of the anticathode the focus has an extremely reduced dimension.

In practice the electrons do not follow exactly the straight prolongations of the lines of force emitted by the filament but it suffices, in order to obtain a focus of minimum dimensions, to place the face of the anticathode further from the filament than its centre of curvature.

In the plane perpendicular to that which contains the filament, the dimension of the focus is defined by the diameter of the filament, the form of the focussing member, the relative position of these two elements and the position of their assemblage relative to the anticathode.

The major axis of the focus may therefore be placed in a plane perpendicular to that which contains the curved axis of the filament, whilst, in ordinary X-ray tubes, the major axis of the focus and of the filament are on the same plane.

So that the dimension of the focus may be very small in the plane of curvature of the filament it may be necessary either to cool the extremities of this filament to limit its emission to its correctly curved central part, or suitably to adjust the electric field in the neighbourhood of these extremities by means of suitable electrostatic members.

It is suitable also to give to the face of the anticathode on which the focus is disposed any appropriate form and to incline its adjacent faces so as to regulate the convergence of the lines of force.

The electron emitting filament may be constituted by an element the emissive part of which is curved and may consist of; a helix with a

2

curved axis and of suitable section or more simply of a wire or by a ribbon.

One can, therefore, regulate the dimensions of the focus, after construction of tube, by variation of the curvature of the filament or of the distance between the filament and the anticathode.

Figs. 1, 2 and 3 represent a tube made in accordance with the present invention.

In these figures: 1 is the anticathode, 2 is a helicoidal filament, 3 is the curved axis of radius r of filament 2, the axis of the curvature of said filament being perpendicular to a plane containing the length of the filament is illustrated at the point 4 on the front surface of 1, but point 4 may be located outside this surface for instance between the filament and the anticathode.

5 5 is a channeled focussing member shown in section, the curved surfaces of which as shown in Fig. 1 are concentric about the centre 4, but it may have a different curvature or even be flat as if the lines 5' and 5'' were straight.

6 is a rod supporting the member 5. 7 and 7' are rods used simultaneously as mechanical supports for filament 2 and as conductors for its heating current. 8 is the housing of the X-ray tube comprising sealed entry points of the rods 6, 7 and 7'.

9 represents lines of force, 10 represents paths of electrons which coincide with the lines of force in the neighbourhood of the filament.

20 The focus is disposed on the surface of anticathode 1 and may coincide with point 4 or not according to where this point is located as already explained.

The members 7 and 7' may have any proportions and be extended towards the filament to limit the emission of the latter to its central part.

40 40 The extremities of the members 1 and 8 at the right of Figs. 1 and 2 are not shown and may be of any suitable known shape and disposition.

45 Figs. 4, 5, 6 and 7 show different forms of the member 5 permitting to secure suitable lines of electric force in the neighbourhood of the extremities of the filament.

In Fig. 4 the member 5 comprises the extremities 5' between which the filament is encased.

In Fig. 5 the member 5 carries the members 17 of the same diameter as that of the filament and located as prolongations of the latter.

55 In Figs. 6 and 7 the members 5 carry mem-

3

bers 18 and 19 of different form from parts 17 but for an analogous purpose.

Figs. 1 and 3 show, besides the general disposition which is the subject of the present invention, a means of adjusting the dimensions of the focus in the plane of the filament by the adjustment of the curvature of the latter, by means of the supports 7 and 7' which can oscillate for this purpose.

11 and 11' are fluid-tight and deformable members soldered, brazed or otherwise sealed on the one hand on the envelope 8, and on the other hand, to the rods 7 and 7'. The members 11 and 11' allow, by their deformability, some turning of rods 7 and 7' about points 12 and 12'. The result is that the extremities 13 and 13' separate when the extremities 14 and 14' converge and conversely; this allows adjustment on the radius r by controlling the distance between 14 and 14'.

15 is an insulating member carrying screws 16, allowing the alteration of distance between 14 and 14'. The member 15 may furthermore be fixed onto the rod 6 or on to any other member rigidly fixed on the envelope 8.

This adjustment device of the radius of curvature of the filament is only given by way of example and any other equivalent method may be used, for instance the deformation of bimetallic supports heated directly or indirectly by the heating current of the filament or by a different current which depends or not on the latter.

Figs. 8, 9 and 10 show an X-ray tube allowing the adjustment of the dimensions of the focus to be made by the control of the distance between the cathode and the anticathode.

In these figures, 21 is the insulating envelope of the tube, 22 is the electron emitting filament. This filament 22 is formed by a simple metallic wire, the axis 23 of which has a radius of curvature r the axis of the curvature of said filament at 24 being perpendicular to a plane containing the length of the filament.

The channelled focussing member 25 is so formed that the centre of curvature of the lines 25' and 25'' is the same as the centre of curvature of the filament. However, these two centres may not coincide and may even be separated by a distance extending to infinity, that is to say that the filament 22 may be rectilinear and the lines 25' and 25'' curved or the filament 22 may be curved and the lines 25' and 25'' rectilinear. 26 is a rod sealed in envelope 21 and carrying the member 25; 27 and 27' are two rods sealed in the envelope 21 and used simultaneously as mechanical supports for the filament 22, and as electric conductors for its heating current.

To filament 22 and to rods 27 and 27' such lengths and diameters are given that the ends of the filament whence emerge the aberrant lines of force may be sufficiently cooled by rods 27 and 27' in order not to emit electrons. 28 is a trunconical tube sealed at one end to the envelope 21 and soldered, brazed or otherwise sealed by the other to the part 29 of the anticathode. The part 29 has a screwed end which carries the movable part 30 of the anticathode which is screwed freely on it.

35 are paths of electrons which, at their origin coincide with radii r but which slightly separate therefrom, later on, so that the focus 34 does not coincide with centre 24.

36 is a ring fixed on 30 which may be magnetic or made of material similar to the rotor of an induction motor.

4

37 is a magnetic circuit placed in the same plane as 36 and comprising poles 38, 39, 40, 41; poles 38 and 40 being excited by the circuit 42 and the poles 39 and 41 being excited by circuit 43.

Circuits 42 and 43 are fed by a common source of direct current 44 and closed successively by switches 45 and 46, in a sequence which depends on the position of the double-switch 47.

The arrangements described above permit experiments to be made to find the best dimensions of the focus by the adjustment of the distance between the cathode 22—25 and face 33 of the anti-cathode. This adjustment is made by rotation of part 30 for instance by communicating to 15 the X-ray tube angular asymmetric accelerations by any known manual or mechanical means. In this case elements 36 to 47 shown in Figures 8, 9 and 10 are useless.

The rotation of part 30 may also be made by 20 means of part 36 and by an oscillating magnetic field produced by elements 37 to 47.

Fig. 8 is, with regard to this, sufficiently clear for it to be understood that if the switches are worked in the following sequence: closure of 45, 25 closure of 46, opening of 45, opening of 46, there is applied to the part 36 a magnetic field the orientation of which alters sharply when switch 46 is closed, which induces currents in 36 and the reaction of this current on these induction fields 30 makes assembly 38—36 revolve through successive angles.

The direction of the rotation of the field and in consequence the direction of the rotation of the anticathode may be reversed by means of 35 the double-switch 47.

In any case, the position of parts 38 to 36 relative to 29 may be shown by means of any suitable marks on parts 29, 30 and 36.

After adjustment of the dimensions of the focus 40 part 29 of the anticathode may be expanded with the double purpose of immobilising the movable part and of obtaining a thermic contact between 29 and 30 favouring the removal of the energy received by the focus. This expansion may be 45 obtained by dudgeonage, or by any other equivalent method.

Figs. 11 and 12 show X-ray tubes made in accordance with this invention and using different means for adjusting the distance between the 50 cathode and the anticathode.

In these figures the same reference numbers represent the same parts or members as in the preceding figures. 50 is an anticathode of an already known type. 51 is a deformable corrugated tube made of metal or suitable alloy so that 55 its dimension parallel to the main axis of the tube may be altered without prejudice to its fluid-tightness.

This tube 51 may be fixed to the envelope 21 60 directly or by means of intermediate tubes 52 and 53 which are sealable or may be soldered to 51 and 21.

Figs. 11 and 12 are only given by way of example and tubes 51, 52 and 53 may be located 65 in any convenient position.

The adjustment of the distance between the members 25 and 50 and the immobilisation of the movable members after adjustment may be made by any known means the description of which 70 would be outside the present patent specification.

Figs. 8, 9 and 10 show, besides the device for adjustment of the distance between the filament and the anticathode, one shape of the latter allowing the adjustment of the electric field in 75 which the electrons are moving.

Part 30 comprises two oblique faces 31 and 32 which form limits to the face 33 on which focus 34 is formed.

The face 33 has therefore a rectangular form, the length of which is equal to the diameter of part 30 and with a much smaller width than this diameter; but the oblique faces 31 and 32 may be replaced by a trunco-conical or pyramidal surface terminated by a circular or polygonal face 33 on which is disposed the focus 34.

What I claim and wish to secure by Letters Patent is:

1. In an X-ray tube, means for improving concentration of the electrons adjacent the focus comprising a focusing member with a channel containing a filament member, at least one part of which has a concave curvature centered adjacent the focus, the axis of the curvature being perpendicular to a plane containing the length of the filament.

2. In an X-ray tube, means for improving concentration of the electrons adjacent the focus comprising a filament member with a rectilinear axis and a focusing member having a channel containing said filament member and a concave curvature centered adjacent the focus, the axis of the curvature of said channel being perpendicular to a plane containing the length of the filament.

3. In an X-ray tube, means for improving concentration of the electrons adjacent the focus comprising a filament member having a concave curvature the axis of which is centered adjacent the focus and a focusing member having a channel containing the filament member and a concave curvature centered adjacent the focus, the axis of the curvature of said channel being perpendicular to a plane containing the length of the filament.

4. In an X-ray tube, means for improving concentration of the electrons adjacent the focus comprising a focusing member with a channel containing a filament member, at least one part of which has a concave curvature centered adjacent the focus, the axis of the curvature being perpendicular to a plane containing the length of the filament, and electrostatic members in the neighborhood of the prolongation of the extremities of the filament member for centering the electric field.

5. In an X-ray tube, means for improving concentration of the electrons adjacent the focus comprising a focusing member with a channel containing a filament member, at least one part

of which has a curvature centered adjacent the focus, the axis of curvature being perpendicular to a plane containing the length of the filament, an anticathode on which the focus lies, and inclined faces on said anticathode, whereby the electric field in which the electrons are moving is suitably regulated.

6. In an X-ray tube, means for improving concentration of the electrons on the focus comprising a focusing member with a channel containing a helical filament member, at least one part of which has a concave curvature centered adjacent the focus, the axis of curvature being perpendicular to a plane containing the length of the filament.

7. In an X-ray tube, means for improving concentration of the electrons adjacent the focus comprising a focusing member with a channel containing a wire filament member, at least one part of which has a concave curvature centered adjacent the focus, the axis of the curvature being perpendicular to a plane containing the length of the filament.

8. In an X-ray tube, means for improving concentration of the electrons adjacent the focus comprising a focusing member with a channel containing a ribbon filament member, at least one part of which has a concave curvature centered adjacent the focus, the axis of curvature being perpendicular to a plane containing the length of filament.
